UNITED STATES PATENT OFFICE.

JAMES McKNIGHT, OF BROOKLYN, NEW YORK.

IMPROVEMENT IN HYDRANT-COVERS.

Specification forming part of Letters Patent No. 154,408, dated August 25, 1874; application filed
July 25, 1874.

To all whom it may concern:

Be it known that I, JAMES McKNIGHT, of Brooklyn, in the county of Kings and State of New York, have invented a new and Improved Hydrant-Cover, of which the following is a specification:

The object of my invention is to provide a simple and cheap means of fastening hydrant-covers, whereby they may be more readily connected and disconnected than they can be as at present arranged, and at the same time be as securely fastened.

Figure 1 is a sectional elevation of my improved hydrant-cover fastening, and Fig. 2 is a sectional elevation.

Similar letters of reference indicate corresponding parts.

I provide spring-catches A on the under side of the cover B, extending down a suitable distance in the hydrant C, and a cam, D, in combination with said catches, to force them out and hold them in notches E in the hydrant, the cam being suspended on the lower end of a spindle, F, which is fitted in a central bearing projecting

from the under side of the cover, and having a socket, G, in the upper end, in which the upper end of the spindle terminates, so that it can only be turned by a wrench, H, which will fit in the socket. The cam will be held in position for keeping the catches in the notches by friction; but a fastening device may be employed for the purpose, if required. Lugs may be used on the walls of the hydrant for the catches, instead of the notches, if preferred.

Having thus described my invention, I claim as new and desire to secure by Letters Patent—

The combination of the spring-catches A, cam D, and a spindle, F, with the hydrant C and its cover B, the hydrant having the notches E for the catches, and the spindle being arranged in a socketed bearing to be turned by a wrench, H, all substantially as specified.

JAMES McKNIGHT.
